ATTORNEY

UNITED STATES PATENT OFFICE.

HIRAM CARDEN, OF DAISY, TENNESSEE.

LIFTING-JACK.

1,260,510.

Specification of Letters Patent. Patented Mar. 26, 1918.

Application filed April 3, 1917. Serial No. 159,498.

To all whom it may concern:

Be it known that I, HIRAM CARDEN, a citizen of the United States, residing at Daisy, in the county of Hamilton and State of Tennessee, have invented certain new and useful Improvements in Lifting-Jacks, of which the following is a specification.

My invention relates to improvements in lifting jacks, and it consists in the constructions, combinations and arrangements herein described and claimed.

An object of my invention is to provide a lifting jack comprising a suitably braced frame including bifurcated members each of which has a plurality of transverse apertures wherein an adjusting bolt may be fitted so that a lever arm may be mounted upon the bifurcated members to obtain a leverage of either the first or third classes.

Another object of the invention is to provide a lifting jack as described, the movable lever arm being adapted to receive an adjustable leg having a foot whereby such objects as the sills of houses, mining cars, etc., may be lifted.

Other objects and advantages will appear from the following specification, reference being had to the accompanying drawing in which:

Figure 1 is a side elevation of the lifting jack showing the adjustable leg on the movable lever as being applied in raising a large object.

Fig. 2 is a plan view of the parts shown in Fig. 1,

Fig. 3 is a section on the line 3—3 of Fig. 1, and

Fig. 4 is a detail perspective view of the adjustable leg.

In carrying out my invention I provide a fulcrum standard 1 which includes the upper and lower bifurcated portions 2 and 3 respectively. The bifurcated portions extend in opposite directions from a web or bridge portion 4. It will be observed from Fig. 3 that the fulcrum standard 1 is an integral structure, although if actual practice may demand, it may be made in sections and bolted together.

Fulcrum apertures 5 of which there is a series are formed in the bifurcated portion 2 of the fulcrum standard 5. An adjusting bolt 6 is adapted to pass through the apertures 5, and form the pivotal connection for a movable lever 7.

A second fulcrum standard 8 is provided,

which is similarly bifurcated at its upper and lower portions as designated at 9 and 10. The bifurcated portion 9 is provided with apertures 11 through which a holding bolt 12 is adapted to pass and serves to secure the movable lever 7 in its adjusted positions should it be found necessary to employ such a bolt in the use of the lifting jack.

In such an instance it will be understood, that pressure brought to bear upon the end of the lever 7 beyond the second fulcrum standard 8, will be difficult to maintain and therefore the use of the holding bolt 12 will be found of great aid.

A bridge bar 13 is secured at its ends as at 14 in the lower bifurcated portions 3 and 10 of the first and second fulcrum standards 1 and 8. It will be observed that the second fulcrum standard 8 is somewhat shorter than is the first fulcrum standard 1. It will also be seen that the standards are not disposed vertically but are inclined at an angle with respect to the bridge bar 13. It has been found from practical experience that this particular construction as applied to the lifting jack illustrated in Fig. 1 is of advantage, in that the lifting jack can be moved up close to an object and the arcuate movement of the movable lever 7 upon its fulcrum bolt 6 compensated for by reason of the rearward inclination of the first fulcrum standard 1.

The movable lever 7 is thickened centrally as at 15. The front end of the lever 7 is provided with a heel 16 which may under certain conditions be applied directly to the object to be lifted. The handle portion 17 of the lever 7 is somewhat narrowed from the thickened portion 15, so that a convenient grip may be gotten thereon. A series of apertures 18 is formed near the front end of the lever while another series of apertures 19 is formed therein near the handle 17. It will be understood from Fig. 1 that the bolts 6 and 12 are adapted to pass through the respective series of apertures 18 and 19.

An adjustable leg 20 having a bifurcated upper end 21 is adapted to be hung upon the front end of the lever 7 by the means of a bolt 22 which passes through apertures 23 in the bifurcated portion 21 and through one of the apertures of the series 18.

A foot 24 is formed at the lower end of the leg 20. It is sometimes desirable and

- necessary to employ the leg 20 as when an object is of such a nature that it cannot readily be engaged by the heel 16 of the lever 7. Such an instance may be represented when a mining car has left the track and tilted over so that no hold can be gotten thereon by the heel 16 of the lever 7. Obviously by forcing the foot 24 beneath the car and then moving the lever 7 upon its fulcrum 6 until the supporting bolt 22 may be passed through the then complementary apertures 23 and 18, pressure then brought to bear on the handle portion 17 of the lever 7 will effect the elevation of the derailed car.
- 15 The operation and application of the device is as follows. The lifting jack frame with its fulcrum standards 1 and 8 is moved up to an object to be lifted and supported in place by the hands of the workmen until the lever 7 is mounted in position on its fulcrum bolt 6 and the heel 16 thereof is brought into engagement with the object and a slight pressure is brought to bear upon the handle 17. It will be understood that the slight pressure on the handle 17 will serve to hold the lifting jack frame in position and it will no longer be necessary to furnish support for the frame through a manual agency.
- 20 The adjustment of the lever having been secured, continued pressure upon the handle 17 will of course move the heel 16 upwardly and thus raise the weight. The holding bolt 12 may be slipped into the various apertures 25 11 in the fulcrum standard 8 as the handle 17 is moved downwardly.
- The adjustment of the lever 7 on the fulcrum standard 1 will be recognized as that of a lever of the first class. Should it be found necessary to change the adjustment so as to form a lever of the third class, the fulcrum bolt 6 may be removed and the holding bolt 12 employed as the fulcrum bolt. It will be understood that at this time the thickened portion 15 will serve as a hand-grip where the pressure is applied and a weight hung upon the heel portion 16 will consequently be elevated.
- 40 Referring again to the specific embodiment as illustrated in Fig. 1 it will readily be observed that upon downward movement of the handle 17 the front end of the lever 7 will move upwardly and the edge of the leg 20 will slide over the rearwardly inclined surface of the fulcrum standard 1. The fulcrum standard 1 thus not only serves 45 in its true capacity as a support for the

fulcrum of the jack but also as a guide for the leg 20 as it is moved vertically.

While the construction and arrangement 50 of the device as illustrated in the accompanying drawing is that of a generally preferred form, obviously modifications and changes may be made without departing from the spirit of the invention or the scope 55 of the claims.

I claim:—

1. In a lifting jack of the class described the combination of a pair of similarly constructed standards, each standard being bifurcated at its ends to form central webs, a bridge bar secured between the bifurcations of the lower ends of the standards, thus spacing the standards apart, a movable lever pivotally mounted upon one standard 70 between the bifurcations thereof, said lever being adapted to be swung within the remaining bifurcation of the remaining standard, means for holding said lever in a set position and an adjustable leg connected 75 to one end of said lever.

2. In a lifting jack of the class described, the combination of a main standard and a secondary standard, said standards having bifurcated ends, thus forming central webs, 80 said standards being parallel to each other and slanting to one side, a bridge bar having its ends positioned in the bifurcations adjacent the lower end of said standards, thus holding said standards against accidental 85 displacement, a movable lever pivotally mounted upon the main standard, said lever being adapted to be swung within the remaining bifurcation of the secondary standard, an adjustable leg pivotally mounted 90 upon one end of said movable lever, whereby when said lever is swung downwardly to elevate the adjustable leg, to lift an article, the slanting of said standard will compensate for the arcuate movement of the end of 95 the lever, thus causing the leg to ride upon the outer surface of the main standard, and said slanting construction also permitting the jack to be moved contiguous to the article to be lifted, although providing sufficient space for the adjustable leg at the end 100 of the lever to which the same is secured.

In testimony whereof I affix my signature in presence of two witnesses.

HIRAM CARDEN.
